(57) **CLAIM**

The ornamental design for a washing machine hose, as shown and described.

DESCRIPTION

FIG. 1 is a perspective view of a washing machine hose according to the present invention;

FIG. 2 is a top view thereof;

FIG. 3 is a left side view thereof, the right side view being a mirror image thereof;

FIG. 4 is a front view thereof;

FIG. 5 is a rear view thereof; and,

FIG. 6 is a bottom view thereof.

The broken away symbols in the drawings indicate that any portion of the article beyond what is shown forms no part of the claimed design.

The broken lines shown in the drawings are for the purpose of illustrating environmental structure and form no part of the claimed design.
